UNITED STATES PATENT OFFICE.

HERMAN E. WINTERHOFF, OF INDIANAPOLIS, INDIANA, ASSIGNOR TO LEEDY MANUFACTURING COMPANY, OF INDIANAPOLIS, INDIANA, A CORPORATION OF INDIANA.

MUSICAL INSTRUMENT.

1,304,435.

Specification of Letters Patent. Patented May 20, 1919.

Application filed March 27, 1916. Serial No. 86,872.

To all whom it may concern:

Be it known that I, HERMAN E. WINTERHOFF, a citizen of the United States, residing at Indianapolis, in the county of Marion 5 and State of Indiana, have invented a new and useful Musical Instrument, of which the following is a specification.

The object of my invention is to produce a musical instrument comprising one or 10 more sounding members, such, for instance, as a bar, tube, rod, plate, etc., capable of producing a desired sound by vibration, each of said members being associated with a plurality of resonators arranged at appropriate points opposite the antinodes of 15 various overtones in such manner as to augment the selected tones, or overtones, whereby the sound of the sounding member may be increased and modified.

20 The accompanying drawings illustrate my invention. Figure 1 is a front elevation of a single chime bar and associated resonators constructed in accordance with my invention; Fig. 2 is a side elevation of the instrument shown in Fig. 1; and Fig. 3 a fragmentary detail of a modification showing means by which the tone quality of the instrument may be varied by temporarily eliminating one or more of the resonators.

25 30 In the drawings, 10 indicates a chime bar supported by a suitable support 10' which will permit proper vibration of the bar when it has been struck or otherwise suitably manipulated. When such a bar has been set into vibration in the manner described, a plurality of sets of vibrations are set up, which produce the fundamental tone and the various overtones which together produce the resultant characteristic sound 35 of the bar.

40 It has heretofore been customary to provide single resonators of suitable length and diameter opposite the middle of the sounding bars, of comparatively short length, such as are used in xylophones, such a resonator operating to augment only the fundamental tone of the bar. This is satisfactory for bars of high pitch, but ordinarily is not satisfactory for long low-pitch bars, because 45 of the extreme length which would be required for the resonator.

50 Vibratile members of the character described, having pitches within the usual

middle register, generally have the fourth overtone predominating, although in higher 55 pitch members there is a gradual approach to a predominance of the third overtone, while in lower pitch members there is a gradual approach to a predominance of the fifth overtone. It is for this reason that it 60 is especially difficult to harmonize chimes, especially those of tubular members, with other musical instruments.

I have discovered that an unexpected richness of tone quality for vibratile members 65 of the character described, and especially those of tubular character, may be produced by a proper combination of resonators so placed relative to the antinodes of the fundamental tone and various overtones of the 70 bar that undesirable overtones, because of the emphasis of desirable overtones, become practically audibly eliminated. By such an arrangement of resonators, I find that I am able to produce with a comparatively short 75 bar, say, for instance, one 30 inches long, a depth and volume of tone which, without the combination of resonators, could not be produced except by an extremely long and heavy bar structurally beyond the practical 80 limits of use or manipulation.

For this purpose, I provide a plurality 85 of resonators 11, 12, 13, 14, 15, 16, etc., placed opposite the antinodes of various overtones of the bar. The tone quality of 90 the chime bar or other vibratile member of the character described, equipped with a set of resonators such as I have described, may be temporarily modified in different ways by preventing the operation of one or 95 more of the resonators, in various combinations, this being readily accomplished by means of shutters 17 which may be moved into or out of position between the chime bar and the mouth of the resonator.

With a vibratile member such as is shown in the drawings, it is important that the suspension means engage the bar at the node of the tone which is intended to predominate and that the guard be placed at another node of the same set of vibrations. In the drawings, therefore, the suspension 100 105 is shown as engaging the bar at a node of the fifth tone of the bar, as this tone is the one selected as the predominant tone for obtaining the particular quality desired.

It will be understood that the point of suspension may be varied so as to select any particular tone or overtone.

It will also be apparent, as indicated in Fig. 2, that the resonators should be placed at proper positions in the length of the bar and should be placed with their mouths close to the bar, but at sufficient distance therefrom to give opportunity for free vibration.

It will be apparent that forms of vibratile members other than the flat bar shown in the drawings, may be used without departing from my invention.

15 I claim as my invention:

1. A musical instrument comprising a vibratile member with a suitable support therefor, and a plurality of resonators associated with said vibratile member coöperatively adjacent antinodes of different overtones of said member.

2. A musical instrument comprising a vibratile member with a suitable support therefor, a plurality of resonators associated with said vibratile member coöperatively adjacent antinodes of different overtones of

said member, and means for temporarily eliminating the resonator effect of one or more of said resonators.

3. A musical instrument comprising a vibratile member and a suitable support therefor engaging the same at a node selected to determine the dominating tone desired, and a plurality of resonators associated with said vibratile member coöperatively adjacent antinodes of different overtones of said member.

4. A musical instrument comprising a vibratile member and a suitable support therefor engaging the same at a node selected to determine the dominating tone desired, a plurality of resonators associated with said vibratile member coöperatively adjacent antinodes of different overtones of said member, and means for temporarily eliminating the resonator effect of one or more of said resonators.

In witness whereof, I have hereunto set my hand at Indianapolis, Indiana, this 22nd day of March, A. D. one thousand nine hundred and sixteen.

HERMAN E. WINTERHOFF.
